No. 781,875.

PATENTED FEB. 7, 1905.

C. FOLTZ & H. L. FULLER.

SMOKE STACK.

APPLICATION FILED SEPT. 19, 1904.

UNITED STATES PATENT OFFICE.

CHESTER FOLTZ AND HORACE LEON FULLER, OF DENVER, COLORADO.

SMOKE-STACK.

SPECIFICATION forming part of Letters Patent No. 781,875, dated February 7, 1905.

Application filed September 19, 1904. Serial No. 225,112.

To all whom it may concern:

Be it known that we, CHESTER FOLTZ and HORACE LEON FULLER, citizens of the United States of America, residing at Denver, in the 5 county of Denver and State of Colorado, have invented certain new and useful Improvements in Smoke-Stacks, of which the following is a specification.

Our invention relates to improvements in 10 smoke-stacks, and is particularly adapted to be used on locomotives in which the exhaust steam from the cylinders is discharged in the smoke-box to increase the draft of the engine.

It is a well-known fact that wherever a rail- 15 road traverses a wooded section of country or a settlement the burning substances which almost constantly are emitted from the chimneys of passing engines have been a menace to the forests and houses along the road, not 20 infrequently resulting in disastrous fires, causing untold loss of timber and other valuable properties.

The object of our invention is to provide a 25 smoke-stack of simple construction in which the sparks and other ignited products of imperfect combustion of the fuel on the grate in the fire-box will be extinguished before they are emitted from the stack into the open, thus practically eradicating the dangers here- 30 above described.

We attain our object by the mechanism illustrated in the accompanying drawings, in which—

Figure 1 represents a vertical section taken 35 through the upper portion of a locomotive smoke-box surmounted by our improved smoke-stack; Fig. 2, a composite view, the left-hand side of which represents a horizontal section taken along the line 2-2, Fig. 1, 40 looking downward, while the right-hand side is a section taken along the line 2^a-2^a, Fig. 1, looking upward. Fig. 3 represents an enlarged vertical section of the upper portion of the smoke-box with base and lower portion of the chimney.

Similar reference characters refer to similar parts throughout the various views.

The smoke-stack or chimney 5 is composed 45 of two concentric hollow cylinders 6 and 7, preferably made of sheet metal, the outer one

of which is surmounted by a diamond-shaped top or bonnet 8, consisting of two truncated cones 8^a and 8^c, placed one above the other and meeting at their largest portion. The inner cylinder 7, extending into the cone-shaped top 8, terminates below an inverted-cup-shaped deflector 9, which is suspended inside the bonnet 8 by means of radially-extending arms 10, which, forming part of the deflector, are secured to the top 8 by rivets or 55 other suitable means. A wire screen 23 is placed across top 8, preferably at the junction of the two cones and a short distance above deflector 9.

Pipes 6 and 7 are erected on and secured to 60 a base 11, consisting of a ring 12 and a surrounding flange 13, by means of which it is bolted or riveted to the arch of the smoke-box 14. The cylindrical portion 12 of base 11 extends in between pipes 6 and 7, thus 65 forming an annular chamber 15 between the two, while the inner pipe 7 of chimney 5 communicates with the interior of the smoke-box by means of a circular opening 16 cut in its arch. 75

17 represents the nozzle of the exhaust-pipe, through which the steam exhausted from the cylinders is discharged into the smoke-box, while 18 indicates the so-called "petticoat-pipe," which forms the conduit 80 for the exhausted steam from the nozzle to the chimney.

19 and 19 are two pipes, which, being suspended from the lower surface of base 11 by means of flanges 20 and 20, communicate with 85 apertures 21 21, extending through the cylindrical portion 12 of base 11, while their lower inwardly-curving extremities terminate at points a short distance below the mouth of exhaust-pipe 17. 90

The outer cylinder 6 of chimney 5 is provided near its lower extremity with two or more hand-holes 22, normally closed by screw-plugs 24 and affording access to the annular chamber 15 when it is desired to remove accumulated matter therefrom or to clean out pipes 19. 95

The products of combustion having passed from the grate in the fire-box through the boiler-tubes into smoke-box 14 are drawn 100

into the inner cylinder 7 of smoke-stack 5 through opening 16, the natural draft of the engine being augmented by the steam escaping through nozzle 17. When striking deflector 9, the heavy ignited partly-consumed substances which, with the smoke and gases, escaped from the fire-box are deflected against the inner surface of cone 8^a of top 8 and fall into the annular chamber 15 between pipes 6 and 7 of the chimney, while the lighter products of combustion, such as smoke and gases, escape through the wire-netting 23 into the open. The exhaust-steam, emitted with considerable speed from nozzle 17, creates a partial vacuum in smoke-box 14, the most perfect vacuum being obtained below the opening of the nozzle or the point where pipes 19 terminate. This fact, in coöperation with the air-pressure in chamber 15, will cause the sparks, cinders, and other heavy substances deflected into said chamber to be drawn through apertures 21 in base 11 and through pipes 19 into the smoke-chamber, from where the moment they leave said pipes they will once more be drawn into cylinder 7 of the chimney. The above-mentioned substances, which, as explained, were burning when they entered the smoke-box, have during this operation been extinguished, in consequence of which, as well as by the friction against the walls of the various pipes, they have been reduced in weight, with the result that when emitted from pipe 7 they will, together with the smoke and gases, escape into the open. In case the sparks or glowing cinders are unusually large or not quite extinguished

when emitted from pipe 7 the second time the above-explained operation will be repeated until the desired lightness has been obtained.

Pipes 19, as shown in the drawings, are for the purpose of increasing their volume made 40 oblong in cross-section. Their shape, however, is not essential to the effective operation of the device and may be altered to suit circumstances. It must, furthermore, be understood that pipes 19 instead of terminating below the mouth of the exhaust-pipe may be bent in opposite direction or to any part of the smoke-box, depending on circumstances and the nature and size of the engine to which 50 they are applied. The shape as well as the relative positions of the other parts of the device may also be changed without departing from the spirit of the invention.

Having thus explained our invention, what 55 we claim is—

The combination with a smoke-box, a steam-exhaust pipe opening therein, a chimney composed of two concentric pipes, the inner one opening in said smoke-box and a deflector 60 mounted inside the outer pipe and above the inner one, of conduits leading from the space between said pipes, their extremities terminating below and in close proximity to the orifice of the exhaust-pipe.

In testimony whereof we have affixed our signatures in presence of two witnesses.

CHESTER FOLTZ.
HORACE LEON FULLER.
